LETTERING GUIDE

Frank P. Kuhl, Bronx, N. Y., assignor to Keuffel & Esser Company, Hoboken, N. J., a corporation of New Jersey

Application September 15, 1943, Serial No. 502,709

2 Claims. (Cl. 33—174B)

1

This invention relates to lettering guides for use in inscribing lettering, numbering or other symbols for descriptions, directions, titles, etc., on drawings, details, maps and other similar delineations.

One object of this invention is to provide a lettering guide of simple construction to enable draftsmen to inscribe neat uniform lettering on drawings without guide lines which necessarily require later removal.

Another object of the invention is to provide a lettering guide which can be used for lettering in either pencil or ink, constructed so that a maximum of guidance is obtained without danger of smudging or blotting.

A further object of the invention is to provide a lettering guide which can be adjusted for letters of various height by means of a simple manipulation.

A still further object of the invention is to provide lettering guides which can be incorporated in other tools of the draftsman, such as triangles, curves, straight-edges, T-squares, drafting machine scales, etc.

Another object of the invention is to provide lettering guides which can be used in conjunction with T-squares and triangles or drafting machines and so provide a guide for lettering at any angle on the drawing.

With these and other objects in view, the invention consists of the arrangement and combination of parts as hereinafter described with reference to the accompanying drawings in which:

Figure 1 is a view in plan with portions cut away of a drafting triangle embodying one form of the present invention.

Figure 2 is a view in plan of the under side of the drafting triangle shown in Figure 1.

Figure 3 is a view in section along the line 3—3 of Figure 1 looking in the direction of the arrows.

Figure 4 is a view in section along the line 4—4 of Figure 2 looking in the direction of the arrows.

Figure 5 is a view in plan of an embodiment of the invention wherein the lettering guide is adjustable.

Figure 6 is a view in elevation of Figure 5 from the left of that figure.

The invention is illustrated in Figure 1 as applied to the conventional 30°—60° triangle normally used by draftsmen. The embodiment of the invention in this type of triangle is for the purpose of illustration only as the invention could be embodied in any other type of triangle, curve,

2

straightedge or other drafting instrument or it could be embodied in rectangular or square members made solely for the purpose of being used as lettering guides.

5 As shown in Figures 1, 2, 3 and 4, one or more tapered grooves 5 of desired width are provided in the triangle 10 which is conveniently made of a transparent plastic material such as Celluloid or cellulose acetate. The tapered grooves 5 are cut to a depth of approximately one-half of the thickness of the triangle 10 and are formed with inclined faces 14 and 15. The bottom 12 of the tapered grooves 5 should correspond to the height of the letters or numerals to be drawn. 10 The intersection of the inclined faces 14 and 15 and the upper face 19 of the triangle 10 forms the edges 16 and 17. Slots 11 of a width corresponding to the width of the bottom 12 of the tapered grooves 5 are cut through the remainder 15 of the triangle 10.

The triangle 10 in the position shown in Figure 1 is in the preferred position for using the guide for forming pencil letters 51. The vertical walls 13 (Figure 3) of the elongated slot 11 20 extend to the face 20 of the triangle 10 which is in intimate contact with the drawing surface 24 and provide an unvarying stop for the point 21 of the pencil 20 thus enabling the draftsman to draw letters 51 of uniform height with the top 25 and bottom edges in straight parallel lines.

By varying the depth of the tapered groove 5 cut in the triangle 10 or the angle of the inclined faces 14 and 15 or both, the horizontal distance from the vertical walls 13 of the slot 11 to the edges 16 and 17 can be made as desired. As the material of which the triangle 10 is made is transparent, these edges 16 or 17 can be made to coincide with the edge of an adjacent line of lettering or other line from which it is to be spaced and the new line of lettering will be spaced therefrom with a predetermined uniform spacing.

By turning over the triangle 10 to the position shown in Figure 2, the lettering guide is in the preferred position for making ink letters 52 by 30 means of lettering pens such as the draftsman's lettering pen 22 shown in position in Figure 4. The vertical walls 13 of the slot 11 provide the guiding means for the writing element 23 of the draftsman's lettering pen 22. The groove portion 35 of the lettering guide particularly between edges 16 and 17 and the inclined faces 14 and 15 prevents contact between the triangle 10 and the ink in the pen 22 or newly formed letters and thus prevents blotting by capillary action drawing the ink between the under face 19 of the triangle 10 or 40

lettering guide and the drawing surface 24. An advantage of continuing the groove 5 to the ends of the lettering guide is that it permits movement of the lettering guide along the edge of a T-square or other straight-edge as the lettering progresses without having any part of the lettering guide come in contact with any of the newly formed letters in the line before they have dried.

It can be readily seen that a lettering guide in the form of a draftsman's triangle or in the form of a square or rectangular lettering guide can be used in conjunction with T-squares, triangles and the scales of drafting machines so that lettering can be placed on a drawing in any desired position and at any angle. The edges 16 and 17 can act as a spacing means in the same manner as previously described. A series of grooves each of a different width permits one instrument to be used for several different heights of letters. For narrower grooves, i. e. smaller letters, the distance from edge 16 and 17 to walls 13 may be correspondingly smaller, if it is so desired.

Figure 5 shows the present invention embodied in the form of an adjustable lettering guide. Guide members 30 and 31 may be made of either opaque or transparent plastic material such as Celluloid or cellulose acetate. The guide members 30 and 31 are joined by arms 32 and 33 to form a parallelogram of the type usually used in draftsman's parallel rules. Threaded pin 38 is inserted through a preformed hole preferably in the center near the end of guide member 30. The threaded portion 49 of pin 38 is journalled in a hole in arm 32 and is fitted with threaded knurled nut 37. The other end of arm 32 is provided with a fixed pin 40 which snugly fits holes 41 in guide member 31. At the other end of guide member 30, arm 33 is rotatably mounted at the center near the end of guide member 30 by any convenient means and is similarly provided with a fixed pin 40 which snugly fits holes 41 in guide member 31. One end of arm 32 is conveniently formed in the shape of a pointer 34 which reads on "Pencil" scale 35 indicating the distance between vertical guide wall 42 of guide member 30 and vertical guide wall 142 of guide member 31. When guide members 30 and 31 are in the position shown in full lines in Figure 5, the adjustable lettering guide is in the preferred position for drawing pencil letters 151. This provides an arrangement resembling that shown in Figure 3. The edges of guide members 30 and 31 are formed as shown in Figure 6 with vertical walls 42 and 142 and a cut away or beveled portion to form the inclined faces 43 and 143. The intersections of the inclined faces 43 and 143 with the upper faces 54 and 154 of the guide members 30 and 31 respectively form the edges 44 and 144 which may be used for spacing. As previously explained, these vertical walls 42 form a stop for the point of the user's pencil so that letters 151 are formed which are of uniform height in even lines with the top and bottom edges parallel.

By releasing the knurled nut 37, the guide member 31 can be moved so that the space between the vertical walls 42 and 142 of guide members 30 and 31 is increased or decreased to the desired extent. When the guide members 30 and 31 are in the desired relative position, the knurled nut 37 is turned on pin 38 so that arm 32 is clamped to guide member 30. The head 39 of threaded pin 38 is preferably made in a square form or otherwise keyed so that pin 38 cannot rotate when knurled nut 37 is turned relative to the pin 38. In all relative positions of guide mem-

bers 30 and 31 from fully closed to maximum open position, the pointer 34 at the end of arm 32 gives an indication on "Pencil" scale 35 of the space between the vertical walls 42 and 142 of guide members 30 and 31 and, therefore, the relative height of the resulting letters 151. If desired, an elongated slot 50 of construction similar to that described for the elongated slots in the 30°-60° triangle shown in Figures 1 and 2 can be formed in guide member 30 to provide a guide for pencil letters of the height most commonly used by the draftsman.

By loosening knurled nut 37 and removing pins 40 in arms 32 and 33 from holes 41 in guide member 31, and swinging arms 32 and 33 across the lower edge of guide member 30, the guide member 31 can be moved to a position on the opposite side of guide member 30 and can be easily reassembled in the position shown by the dotted lines in Figure 5. In this position, the vertical wall 45 of guide member 30 is brought opposite the vertical wall 145 of guide member 31 and pointer 34 of arm 32 will read on "Ink" scale 36. The edge of guide member 30 at vertical wall 45 and the edge of guide member 31 at vertical wall 145 are preferably constructed as shown in Figure 6 with the under face 56 of guide member 30 and the under face 156 of guide member 31 formed with reentrant cut away portions 46 and 146. This construction removes the vertical guide walls 45 and 145 from intimate contact with the drawing surface and prevents possible blotting by capillary attraction drawing the ink between the lower faces 56 and 156 of guide members 30 and 31 respectively and the drawing surface. This construction also permits moving the lettering guide along a T-square or straightedge as the lettering progresses without blurring the newly formed letters in the line before they have dried. The edges 47 and 147 of the cut away portion 46 and 146 may be used for spacing guides as previously described.

The construction shown in Figure 5 represents only one of many possible embodiments of the invention in an adjustable lettering guide. Many variations from this construction are possible. For instance, it is possible rotatably to mount arms 32 and 33 at the center and near the ends of guide member 31 and provide threaded pins 40 and knurled nuts similar to 37 and 38 at both ends of guide member 31 and to provide holes in the ends of arms 32 and 33 which are journalled on said pins 38. With this construction, to change from the arrangement for pencil lettering to ink lettering, both knurled nuts would be removed and the arms 32 and 33 removed from the threaded pins 38. The guide member 31 would then be moved to a position on the opposite side of guide member 30 and the holes in arms 32 and 33 placed over the threaded pins 38 and the knurled nuts 37 rethreaded on the threaded pins 38 and both knurled nuts 37 tightened when the guide members 30 and 31 are in the desired position. It can be seen that the advantages of the present invention apply equally to this construction as to the construction previously described.

The foregoing description of preferred embodiments of my invention is intended to be illustrative of the invention since many modifications and other forms within the scope of the appended claims will occur to those skilled in the art.

I claim:

1. A lettering guide comprising a parallel surfaced member having two opposed vertical walls

each meeting one surface of said member at substantially a right angle to form a slot and two other walls meeting the other surface of said member to form a groove, the width of the groove being greater than the width of the slot and the length of the groove being equal to the dimension of the parallel surfaced member in the direction of the length of the groove whereby a continuous groove is provided so that the guide may be moved parallel to the groove without engaging a sheet beneath it where letters may have been drawn through the slot.

2. A lettering guide comprising a parallel surfaced member having two opposed vertical walls each meeting one surface of said member at substantially a right angle to form a slot and two other walls meeting the other surface of said member to form a groove, the width of the groove being greater than the width of the slot, said groove in the direction of the length of the groove extending longitudinally to the edge of the said member whereby a continuous groove is provided so that the guide may be moved parallel to the groove without engaging a sheet beneath it where letters may have been drawn through the slot.
